COMBUSTION APPARATUS

Robert A. Foresman, Prospect Park, Pa., assignor to Westinghouse Electric & Manufacturing Company, East Pittsburgh, Pa., a corporation of Pennsylvania

Application August 26, 1936, Serial No. 97,879

3 Claims. (Cl. 126—182)

My invention relates to grate structures for combustion apparatus of the rotatable circular grate type and it has for an object to provide an improved structure of this kind.

5 Further objects of my invention are to provide an improved grate structure which may be readily manufactured and assembled and which will be reliable in operation.

A still further object of the invention is to prevent short circuiting of air from the windbox to the combustion chamber around the periphery of the grate.

These and other objects are effected by my invention, as will be apparent from the following description and claims, taken in connection with the accompanying drawing, forming a part of this application, in which:

Fig. 1 is a vertical sectional view of a boiler furnace having my improved grate structure applied thereto and is taken along the line I—I of Fig. 2;

Fig. 2 is a plan view of the grate structure and supporting base shown in Fig. 1 with the boiler and a portion of the fuel supporting grate members removed; and,

Fig. 3 is an inverted view of a grate member shown in Figs. 1 and 2.

While applicable to various forms of heating structures or furnaces employing circular grate structures, my invention is particularly adaptable to fluid heating boiler furnaces of the annular, rotating grate type, one form of which is disclosed in my copending application, Serial No. 57,332, filed January 3, 1936 and assigned to the Westinghouse Electric & Manufacturing Company. In this form of furnace, fuel is delivered to a portion of the grate and is progressively burned as it is advanced through the combustion space; the ash being deflected radially from the grate after the latter has travelled a predetermined distance, usually somewhat less than 360°.

Reference will now be had to the drawing wherein the grate structure, generally indicated at 10 is rotatably carried by a base member 11 which may serve to support a fluid heating structure such as, for example, a boiler 12. The base 11 may include a cylindrical outer wall 13, a center column 14 and a horizontal wall member 15 carried by the outer wall 13 and center column 14. The wall 15 includes relatively large openings, shown at 16 in Fig. 1, for passage of air to the grate structure 10, and serves as a trackway for rotatably supporting the grate structure. The walls of the base 11 define a windbox 17 be-

neath the grate 12 which may be supplied with air for combustion in any suitable manner.

As shown in Fig. 1, the boiler may include an outer water wall member, 18, carried by the wall 13 of the base 11, and a center drum 19 having a fluid space 21, which drum 19 may be supported by the center column 14.

In accordance with my invention, the grate structure 10 includes a plurality of frame segments 22 which are disposed in a circle for defining an annular frame structure. I have shown in Fig. 2 eight such segments constituting the frame but the number employed may be more or less depending upon the size or design of the grate frame. Each segment 22 includes inner and outer arcuate portions 23 and 24, respectively, which are connected by radial arms or spoked portions 25 whereby relatively large air passages 26 are formed in the segments 22.

The inner and outer arcuate portions 23 and 24 of the assembled segments 22 define annular bearings for the grate 10 and slidably rest upon the trackway or wall 15. A groove 27 is cut or suitably formed in the faces 28 of the inner arcuate portions 23 within which a ring 29 is disposed. The latter is rotatably disposed about the center column 14 and locks the inner ends of the segments 22 in horizontal alignment. The ring 29 may function to maintain the grate structure 10 substantially coaxial with the center column 14. The outer arcuate portions 24 of the segments 22 are cut away as shown at 31 in Fig. 1 and a ring 32 is disposed in the cut-away portion for maintaining the segments 22 in engagement one with the other. A plurality of bolts 33 may be threaded in the respective segments 22 with their heads extending over the ring 32 as shown in Fig. 1, for preventing upward movement of the ring 32. The various segments 22 are provided with depressed portions or seats 34 for a purpose to be referred to hereinafter.

The fuel supporting portion of the grate structure 10 includes a plurality of arcuate grate members 35 assembled in a circle upon the frame segments 22 as best shown in Fig. 2. Each of the members 35 may include a plurality of projections 36 extending upwardly from the upper surface thereof and a plurality of air openings 37 extending through the projections 36, respectively. It will be understood that other forms of passages for air may be employed as they form no part of the present invention. A grate member of the type shown at 35 in the present application is, however, disclosed and claimed in my copending application, Serial No. 96,740, filed

August 19, 1936 and assigned to the Westinghouse Electric & Manufacturing Company.

As best shown in the inverted view, Fig. 3, the members 35 include, on their under sides, radially extending ribs 38 for providing the desired amount of strength against deflection under heat. Projections 39 are formed on the under side of the grate members 35 for engagement with the seats 34 in the frame segments 22. A depressed portion or notch 41 is formed on the under face of the grate members 35 adjacent the outer edges thereof and registers with the heads of the bolts 33. Accordingly, excessive movement of the grate members 35 with respect to the frame members 22 is prevented by the bolt 33 and projections 39 which engage the notches 41 and the seats 34, respectively.

Rotation of the grates may be effected in any suitable manner, as by a pawl and ratchet mechanism shown at 44. The latter preferably includes ratchet teeth 45 formed on the under side of the arcuate portions 24 of the frame segments 22. A pawl 46 may be pivotally supported by an arm 47 carried by a shaft 48, which pawl engages the teeth 45 as the shaft 48 is oscillated and thereby effects step by step rotation of the grate structure 10. Oscillation of the shaft is effected in any well known manner.

An air seal may be provided at the outer periphery of the grate 10 by providing upturned arcuate flange portions 51 on the upper side of the grate members 35, which portions 51 define an annular flange above the outer periphery of the grate 10. A fixed annular flange 52 may extend downwardly within the flanges 51 and may have its bottom edge 53 spaced above the members 35. Accordingly, a working space 54 is defined between the flanges 51 and 52 which fills with ash during operation. Flow of air to the space above the grate 10 through the annular space 54 is prevented by the accumulated ash and therefore defines a seal.

The various elements of the grate 10 are designed with proper clearance for permitting expansion and contraction, during temperature changes. The inner ring 29 is suitably dimensioned to provide clearance between it and the frame segments 22 and functions principally as a locking member for preventing vertical displacement of one segment 22 with respect to another. A defective grate segment 22 may be removed from the grate assembly by raising the outer ring 32 and withdrawing said frame segment 22 radially from the inner ring 29. A replacing segment 22 may be inserted radially over the ring 29 and is then locked in place by lowering the outer ring 32. The outer ring 32 may be proportioned to provide clearance between it and the frame segments 22 whereby radial and circumferential expansion of the frame segments 22 is permitted. As described heretofore, the heads of the bolts 33 prevent displacement of the ring 32.

Expansion of the grate members 35 is permitted as they rest by gravity upon the frame segments 22 and are not rigidly secured in any man-

ner. Objectionable displacement of the members 35 on the frame segments 22 is, however, prevented by the heads of the bolts 33 and by the projections 39 as described heretofore.

From the foregoing, it will be apparent that I have provided an improved form of structure for supporting the grate members of an annular furnace structure.

While I have shown my invention in but one form, it will be obvious to those skilled in the art that it is not so limited, but is susceptible of various changes and modifications without departing from the spirit thereof, and I desire, therefore, that only such limitations shall be placed thereupon as are imposed by the prior art or as are specifically set forth in the appended claims.

What I claim is:

1. In an annular grate structure, the combination of a plurality of segments having inner and outer arcuate portions and arranged in side-by-side relation for defining an annular frame, each of said inner arcuate portions having a slot formed in the inner face thereof, a center column about which the frame segments are disposed, a ring disposed in said slots and encircling the center column, a plurality of grate members carried by the annular frame, and means for rotating the frame and the grate members carried thereby.

2. In an annular grate structure, the combination of a plurality of segments having inner and outer arcuate portions and arranged in side-by-side relation for defining an annular frame, each of said inner arcuate portions having a slot formed in the inner face thereof, a center column about which the frame segments are disposed, a ring disposed in said slots and encircling the center column, an outer ring encompassing the segments and maintaining the same in engagement one with the other, a plurality of arcuate grate members carried by the frame segments and having air passages therein, means for preventing movement of the grate members with respect to the grate segments, and means for rotating the frame segments and the grate members carried thereby.

3. In an annular grate structure, the combination of a plurality of segments having inner and outer arcuate portions and arranged in side-by-side relation for defining an annular frame, each of said inner arcuate portions having a slot formed in the inner face thereof, a center column about which the frame segments are disposed, a ring disposed in said slots and encircling the center column, an outer ring encompassing the segments and maintaining the same in engagement one with the other, a plurality of fastening devices secured in said frame segments and having respective head portions overlying the outer ring for maintaining the same in position, a plurality of arcuate grate members carried by the frame segments and having air passages therein, means for preventing movement of the grate members with respect to the grate segments, and means for rotating the frame segments and the grate members carried thereby.

ROBERT A. FORESMAN.
